212,571

COMBINED SURGICAL INSTRUMENT CLEANER AND STERILIZER

Thomas E. Eaton, Hawthorne, Calif., assignor to Vernitron Corporation, Farmingdale, N.Y., a corporation of New York

Filed Oct. 3, 1967, Ser. No. 8,853

Term of patent 14 years

(Cl. D83—1)

Fig. 4.

Fig. 2.

Fig. 1.

Fig. 3.

FIG. 1 is a front perspective view of a combined surgical instrument cleaner and sterilizer, showing our new design;

FIG. 2 is a front elevational view thereof;

FIG. 3 is a left side elevational view thereof; and

FIG. 4 is a top plan view thereof.

The side of the sterilizer not shown is like the side shown, while the back is substantially the same in appearance as the front thereof.

I claim:

The ornamental design for a combined surgical instrument cleaner and sterilizer, substantially as shown and described.
